UNITED STATES PATENT OFFICE.

NATHANIEL JOSEPH LITTLE, OF ST. PAUL, MINNESOTA.

BOX-LID SUPPORTER.

SPECIFICATION forming part of Letters Patent No. 684,442, dated October 15, 1901.

Application filed December 17, 1900. Serial No. 40,102. (No model.)

To all whom it may concern:

Be it known that I, NATHANIEL JOSEPH LITTLE, a citizen of the United States, residing at St. Paul, in the county of Ramsey and 5 State of Minnesota, have invented new and useful Improvements in Box-Lid Supporters, of which the following is a specification.

My invention relates to improvements in box-lid supporters, the object being to provide simple and inexpensive means for automatically supporting the hinged lids of boxes when open.

To this end my invention consists of a flexible tongue attached to the lid and a guide or 15 slot formed in the rear wall of the box. The free end of the tongue slides in this slot or guide, but fits so snugly therein that the movement of the tongue is retarded by friction.

In the accompanying drawings, forming 20 part of this specification, Figure 1 is a perspective view of a box, showing its lid open and having my support attached thereto. Fig. 2 is a detail sectional view of Fig. 1, taken on the line XX. Fig. 3 is a similar section showing the lid closed. Fig. 4 is a modified form 25 of construction, showing the guide formed by a groove in the rear wall of the box instead of by a cleat, as shown in the preferred construction.

30 In the drawings let A represent the body of the box and B the lid, which is hinged at 2 to the rear wall 3 of the box. The guide 4 is formed between the rear wall of the box and the cleat 5 and is adapted to receive the 35 free end 6 of the flexible tongue 7, which is carried by the lid. The cleat is nailed at 8 or otherwise fastened to the rear wall. As shown the tongue is fixed upon the lid by nails 9; but it is obvious that other means may 40 be applied for attaching the parts. The relative position of the tongue and guide are such that the free end of the tongue is adapted to slide in the guide and bend between the lid and slot as the lid is swung. The tongue must 45 fit to the slot or guide closely, so that the friction between the two members will be suffi-

cient to support the lid at any desired angle to the box. In the alternate construction shown in Fig. 4, instead of using a cleat inside the rear wall of the box to form the guide, 50 as shown in the preferred construction, the rear wall is grooved at 10 receive the free end of the tongue.

Having described my invention, what I claim as new, and desire to protect by Letters 55 Patent, is—

1. A device of the class described, consisting of a box and hinged lid joined together by a non-resilient flexible tongue attached to the lid and a guide in the rear wall of the box; 60 said guide being adapted to receive and engage the free end of the tongue.

2. A device of the class described, consisting of a box and hinged lid movably joined together by a flexible tongue on the lid and 65 a slot adapted to receive and form a frictional engagement with the tongue in the box.

3. The combination with a box, of a lid carrying a tongue, and a wall of the box recessed to receive and form a frictional connection 70 with the free end of the tongue; said tongue being adapted to bend and support the lid when open.

4. A box-lid supporter, consisting in combination with the box and its lid of a non-resilient flexible tongue carried by one member 75 and a slot in the other to receive and form a frictional engagement with the free end of the tongue.

5. A box-lid supporter, consisting of a non-resilient flexible tongue carried by the lid, and a slot formed between the back wall of the box and a cleat upon the same into which slot the free end of the tongue is adapted to fit snugly. 80

In testimony whereof I have signed my name to this specification in the presence of two subscribing witnesses.

NATHANIEL JOSEPH LITTLE.
